(57) **CLAIM**

The ornamental design for a pendant, as shown and described.

DESCRIPTION

FIG. 1 is a front perspective view of a pendant, showing my new design. The broken line showing of environment is for illustrative purposes only and forms no part of the claimed design.

FIG. 2 is a front elevational view of the pendant of FIG. 1.

FIG. 3 is a top plan view of the pendant of FIG. 1.

FIG. 4 is a bottom plan view of the pendant of FIG. 1.

FIG. 5 is a left side elevational view of the pendant of FIG. 1.

FIG. 6 is a right side elevational view of the pendant of FIG. 1; and,

FIG. 7 is a rear elevational view of the pendant of FIG. 1.
